OVEN FOR COKING OF COAL

Franz Puening, Hinchley Wood, England

Application September 12, 1940, Serial No. 356,479
In Great Britain December 8, 1939

8 Claims. (Cl. 202—105)

This invention relates to the coking of coal and, although not exclusively, is particularly concerned with by-product fire-brick ovens, comprising movable, vertical heating walls formed internally with flues in the shape of communicating horizontal passages disposed one above the other and through which are passed in series hot combustion gases, the coking chambers being arranged each between a pair of such walls.

In some known ovens of this type most of the air required for combustion is introduced into the lowest horizontal flue-passage as also is a major portion of the fuel gas, for instance coal gas, this latter portion being sufficient to raise the combustion air in the lowest flue-passage to the temperature desired for coke making. Thereafter the hot combustion gases with an excess of air, pass horizontally through the entire length of the lowest flue-passage and then rise to the passage above, where they receive a new injection of coal gas, thus re-establishing the desired coking temperature. After having traversed the second flue-passage the gases turn up into the third passage receiving a third injection of coal gas, and this process is repeated several times until the gases finally reach the highest passage, whence they are withdrawn through a vertical waste outlet conduit located near the end of the wall.

A great drawback of the type of oven described above lies in the practical impossibility of withdrawing the burnt or partly burnt combustion gases from the top flue-passage without incurring leaks of coal distillate gas from the coking chamber into the vertical waste outlet conduit. The combustion gas volumes used in large coke ovens are very considerable, and naturally require large diameter outlet conduits. A large conduit, however, weakens the structure of the brick wall, especially if those sides of the outlet conduit which face the coal are large. The danger arises, therefore, that coal distillate gas may leak through such large surfaces from the coking chamber into the outlet conduit. The surfaces could of course be reduced in size by making the vertical outlet conduits narrower, but in this case higher velocities and higher suction have to be employed in the conduits, increasing in turn the danger of gas leaking into the conduits from the coking spaces. An improvement on this arrangement was made in the older ovens by making the heating walls between the coking chambers extremely thick, and by locating the conduit as far as possible away from the coking chambers. These thick walls were, however, expensive. Furthermore, even thick walls do not prevent

leakage of coal distillate gas into the outlet conduit when the ovens have been in use for some time, because the coal gas produced in the coking chambers (depending upon the quality of the coal) often builds up a considerable pressure before escaping into the collecting main. Leaks of coal gases into the outlet conduits of older ovens were thus often considerable, resulting in serious economic losses of by-products. These leaks also increased the waste heat temperature, at the expense of valuable surplus gas that might be sold at a profit.

An even more serious result, however, was the damage done to the outlet conduits. In normal operation, temperature variations in the brick-work cannot be avoided when the oven doors are opened, the hot coke is discharged and wet coal enters. These variations create movement in the brick joints near the doors, finally disintegrating the mortar and causing considerable leaks in the joints, so that coal distillate gas, due to the high pressure difference existing between the coking chamber on the one hand and the outlet conduit on the other tends to enter the outlet conduit with some force, overheating, fusing and finally destroying the conduits and the ovens.

These conditions therefore fixed a definite limit to this type of oven. In fact these ovens usually contained only five or six horizontal flue-passages superposed in each wall, because a greater number of such passages would require still more suction, making the operation of the oven quite unsafe.

With the present invention, however, ovens containing ten to twenty superposed horizontal flue-passages and high coking speeds are possible.

It is an object of the present invention to effect improvements upon this type of oven which are such that it can be used for modern large scale carbonisation at medium and low temperatures.

It is another object of the invention to provide an oven in which the high suction required in the outlet conduits and header is prevented from acting upon the joints of the coking chamber walls.

It is another object of the invention to ensure that distillate gases leaking from the coking chamber pass into a heating flue where they mix and are burnt with the heating gases.

It is another object of the invention to provide a heating wall in a coke oven in which the supporting means for internally positioned outlet conduits or the brick portions intermediate the conduits and the walls that abut the walls of

the coking chamber are insulated against the possibility of providing communicating channels between the external coking chamber and the interior of said outlet conduits.

It is another object of the invention to provide a coking oven having a coking wall in which the horizontal flue-passages and the return bends at the ends of the passages through which the gases rise upwardly from passage to passage are so shaped and so heated that the buoyancy of the hot combustion gases rising in the wall becomes a maximum while the resistances of the flues opposed to the travel of these gases becomes a minimum, so that either no suction or only a small one is required at the entrance to the vertical outlet conduits for the withdrawal of the gases from the wall.

Other objects and advantages of the invention will become apparent from the description of a preferred form of the invention which will now be described with reference to the accompanying diagrammatic drawings in which:

Figure 1 is a sectional elevation of a portion of a coke oven battery showing two coking chambers;

Figure 2 is a sectional elevation taken on the line 2—2 of Figure 1 and

Figure 3 is a section on the line 3—3 of Figure 2.

The coke oven illustrated comprises two coking chambers 5 and 6 each of which is formed between a pair of movable walls 7 and 8 or 8 and 9 respectively, built of refractory bricks jointed together. An oven of this type is described and claimed in my co-pending patent application No. 282,785 filed July 4, 1939 (2,240,575 issued May 6, 1941). Each coking chamber is sealed at top and bottom by doors 10 and 11 respectively, and at its sides by luting material 12, the doors 10 and 11 being removable for charging and discharging, for which purpose also the walls 7, 8 and 9 are movable.

Each wall 8, for example is formed internally as a flue, indicated generally at 13, through which heating gases are passed so as to heat up the sides of the wall and thus to effect coking of coal charged into the coking chambers 5 and 6.

The flue 13 consists of superposed horizontal flue-passages 14, 15, 16, 17 and 18 which are in communication with each other at alternate ends. All or most of the air for combustion is injected into the lowermost flue 14 together with a major portion of the fuel gas, through burners 19 and 20 and passages 21 and 22 respectively, in the brickwork around the lowermost flue. By this means any desired temperature, for example 800° C. may be achieved in the lowermost flue. If desired, further fuel gas, and possibly a little air, may be injected into the lowest passage 14 through burners 23 and 24 and passages 25 and 26. The burning gases pass along the flue 14 to the left (Figure 2) and up into the passage 15 above, around the carefully smoothed bend 27. It will be seen that the combustion gases entering through the opening 25 assist the upward motion of the burning gases due to their natural buoyancy. From the flue-passage 15 the heating gases pass around the carefully smoothed bend 28 into the flue-passage 16 above, being again assisted in their upward motion by a relatively small quantity of fuel gas injected through the opening 29. From the flue 17 the heating gases pass around the bend 30 into the topmost flue-passage 18 being, if desired, again assisted in their upward motion

by fuel gas injected through the opening 31 which is shaped and designed to project the fuel gas on to the side face 30 of the flue, since greatest radiation occurs from the side faces and hence provision may have to be made in this manner for keeping up the temperature of these side faces. Openings 32 are provided in order to give opportunity for the introduction of additional fuel gas, whilst opening 33 is provided in order to heat up the dead end 34 which would not otherwise receive any heating gases. As a general rule air is injected or drawn into the wall only through passages 21 and 22, all other burners either receiving no air or only sufficient air to initiate combustion, utilising the air already injected through the openings 21 and 22. The burners 23 and 24 also serve merely to maintain the temperature achieved by the gases issuing from the burners 19 and 20.

From the topmost flue-passage 18 the heating gases are withdrawn via a pair of vertical conduits 35 and 36 which pass downwardly through the partitions 37 between the flue-passages into a horizontal header 38 which emerges from the wall at the level of the lowest flue-passage 14, the header 38 being bolted to a pipe 39 leading to a chimney (not shown), in such a way as to permit motion of the wall.

As shown (in Figure 3) the vertical conduits 35 and 36 are circular but might well be oval, in order to allow a freer passage for the horizontally moving heating gases. Furthermore, as shown in Figure 1, the horizontal header 38, which is of rectangular section, emerges at the level of the lowest flue-passage, but it might equally well emerge at the level of any of the lower flue-passages, as for instance indicated in Figure 2 at 38—A.

In practice, any number of exit conduits 35 and 36 may be used and they may be disposed well to one end of the flue, whilst the header 38 might emerge downwardly from the flue. Again, the flue-passages might be arranged other than horizontally without departing from the scope of this invention.

As the heating gases rise through the flue the resistance to flow, due to friction and due to the changes of direction, act against the upward movement due to the natural buoyancy of the gases, and the flue is designed so as to make these opposing forces roughly equal. Thus the flue-passages are shaped and rounded as at 27, 28 and 30 for example, and the burner passages 25, 29 and 31 for example, are so arranged to assist the natural buoyancy and make the upward force if possible a little greater than the frictional resistance, so that a very small suction is established in the lowest flue 14, just sufficient to cause the air to enter the flue, while in the uppermost flue possibly a slight pressure is created. Subsequently, after having reached and traversed the top flue 18 the heating gases are drawn down through the conduits 35 and 36 into the horizontal header 38 and thence to the chimney. The suction required at the inlet to the conduits 35 and 36 is therefore very small or even zero, whilst maximum suction exists in the header 38.

In the case illustrated, the conduits 35 and 36 abut against the partitions 37 which in turn abut against the sides 40 (Figure 3) of the coking chambers, whilst the header 38 is supported by brickwork at various points along its length, which in turn abuts against the coking chamber walls. At these points it would be possible for

distillate gases within the coking chamber to leak through and continuous joints in the brick-work directly into the conduits, which it is highly desirable to avoid for the reasons given above. To avoid such contingencies, therefore, passageways 41 are placed in the way of all joints 42 which are continuous between the coking chamber and in communication with joints 43 in the conduits. The passageways 41 communicate such joints 42 with the flue 13 and thus by-pass into the flue 13 any gases that may leak through the joints 42, and in this way prevents their continuation onward to joints 43 directly. With respect to the header 38 where supported by brickwork abutting the coking chamber walls 40 passageways 45 and 46 are provided in alignment with joints 44 for the same purpose as are passageways 41.

As shown in Figure 2, the header 38 projects well clear of the coking wall but even in this case the passageway 45 is arranged between the header joints and the coking wall joints even though the former lie outside the flue space; this is because although the header joints are outside the coking wall it would be possible for distillate gases to leak along the brickwork 48 and into the conduit via those joints of the conduit which are external of the flue-space.

It will be seen that the major part of the exterior surface of the conduits 35 and 36 and of the header 38 lie in the flue-space so that gases leaking from the coking chambers for the most part escape into the flue-space, as is desired, and it is only at locations where the conduits and the header, or the supports for them, abut against the coking chamber walls that it is necessary to provide the passageways 41, 45 and 46, for bypassing possible leaks in the joints of the coking wall chamber from the joints in the conduits or header.

As has been stated above, with the known arrangements the pressure in the header is always a negative one, whilst the pressure in the flue-space might be approximately zero and the pressure in the coking space is often a high positive one. Hence there is a strong tendency for the distillate gases to leak out of the coking chamber into the conduits and header. In the present arrangement, however, the provision of the bypassing passageways ensures that leaking distillate gases cannot force their way directly into the conduits or header but will escape into the large flue-space 13 where they mix and are slowly burnt with the heating gases, thus being utilised and avoiding damage by overheating to the conduits or the header. On the other hand in case of leaks in the header, due to the high suction existing in it, the by-passing passageways guarantee that burnt gases will enter the header and not coal gases.

The external joint between the header 38 and the chimney pipe 39 is sealed with luting material to avoid the entrance of air.

It will be seen that with this arrangement the pressure difference tending to force distillate gases from the coking chamber into the outlet conduits and header is reduced to the pressure of the distillate gas itself, the pulling force of the suction inside the header or conduits having ceased to assist. Furthermore, coal distillate gas, if it still succeeds in much reduced quantity in forcing its way through the joints of the coking wall, can now only enter into the combustion flue proper either directly or through the passageways 41, 45 and 46, where, due to the large size

of the flue, they cannot easily cause superheating. The combustion flues are furthermore in contact with the colder coal, and they are therefore not easily overheated. Furthermore, in these flues, the calorific value of the coal distillate gas would be usefully employed by being added to the combustion gases thus assisting the coking process before entering the chimney.

The invention is applicable to brick-built ovens 10 of the type described, whether the ovens or oven walls be stationary or movable.

All the waste heat conduits and headers are isolated from the coking walls themselves, in the sense that every joint in these pipes is surrounded 15 by the combustion space or a space in communication with the combustion space.

This isolation permits the use of very considerable suction inside the outlet conduits and suction header, which in turn permits the members 20 to be given small diameters. The conduits and header are preferably located in the vertical centre plane of each wall, at an ample distance from the interior surfaces of the two coking walls, so that the combustion gases flowing through the 25 horizontal flue-passages find ample passage on each side of the pipes. The horizontal brick partitions between the superposed horizontal flue-passages are built of large horizontal brick slabs touching each other, and a vertical outlet conduit may penetrate through the centre of one of these slabs or between two adjoining slabs. In the latter case, there is a possibility of one or 30 two joints of the vertical conduits being located between two adjoining slabs. In conformity with the present invention, the high suction in the conduit is, however, prevented from continuing between the two slabs till it reaches the coking wall in contact with the coal, by the passageways 41 mentioned before.

40 The vertical outlet pipes are preferably not cemented together with the coking wall brick-work, so that temperature expansions and contractions of the brickwork or deformations due to coal pressure do not endanger the pipes.

45 The conduits may be round or oval and a plurality of conduits are employed in order to keep their diameter and the width and cost of the oven wall down.

The conduits are composed of individual 50 relatively short sections which preferably rest upon each other, thus forming joints of sufficient tightness. Or the conduits may rest upon the horizontal brick partitions. The lowest of the 55 vertical conduit sections rests upon the horizontal outlet header, which is securely held in place, so that leaks are avoided. If, however, small leaks occur, it is only combustion gas that enters the conduits, so that no harm is done, especially as the temperatures of the gases inside and outside the conduits are practically equal.

60 The main principle that every joint in the outlet pipe system is surrounded by parts of the combustion flue-space is continued until the outlet header has reached the outside of the heating wall where, if a leak occurs, air instead of coal distillate gas is drawn into the header; or it is continued till the outlet header is so far removed from the coking space that due to the great thickness of intervening brickwork, a leak of coal distillate gas into the header has become impossible.

This system is therefore safe against coal gas leaks and so the employment of a power driven fan creating a high suction in the outlet conduits and header is possible. Thus large volumes of

waste gases can be removed from large but relatively thin and inexpensive coking walls.

The horizontal outlet header may be made short, with the result that one of the vertical conduits may be located near the burners. Overheating of this conduit may be avoided by the provision of two burners, in each flue-passage, straddling the conduit. Overheating may be further avoided by locating one of these burners at a higher elevation. The conduit next to the burners may also be made of a higher quality firebrick.

The burning of vertical gas flames below the return bends as at 25, 29 and 31 has furthermore the advantage of supplying a greater amount of heat to the internal narrow vertical faces of the walls. Thus, the ends of the flue-passages are well heated for their coking task and furthermore additional buoyancy is created in the vertical return bends.

Further control may be achieved by providing adjustable dampers that may be positioned partially to cover the vertical communication passages between two superposed horizontal flue-passages, in case of excessive buoyancy of the gases.

The new oven principle can of course be used also for the distillation of non-coking coal, oil shale, lignite, peat, etc.

By virtue of the new arrangement, the serious objections to the old ovens with horizontal flues are overcome. Because the fear of high suction in the outlet conduits and headers is eliminated, very large walls can now be built, and their form can be improved by reducing their horizontal length and greatly increasing their vertical height, which is particularly essential for ovens with vertical charging and discharging of coal and coke. This greater height can now be subdivided into many horizontal flue-passages, each of which is equipped with one or more burners, except perhaps the one or two top flue-passages. These improvements produce the much better heat distribution essential for medium or low temperature coking in narrow coking chambers of for instance 3" to 7" width whereby a great increase in the coking capacity of the ovens is obtained.

I claim:

1. In a coke oven, a hollow heating wall adjacent a coking chamber, said heating wall being constructed of elements jointed together to comprise a system of internal heating flues, means for supplying heating gases to said flues, a conduit comprising jointed elements within said heating wall for withdrawing waste heat therefrom, jointed elements within said heating wall intermediate to said coking chamber and said conduit, said conduit being spaced from the inner surfaces of said heating wall except for certain of said jointed elements, the joints of said certain jointed elements being communicated with the heating flues by substantial passageway means, whereby possible channels of joint communication between the coking chamber and the interior of said conduit are intermediately bypassed into the said heating flues.

2. In a coke oven, a hollow heating wall adjacent a coking chamber, said heating wall being constructed of elements jointed together, a plurality of internal jointed baffle walls alternately spaced from the ends of the said heating wall to form a single heating passage encompassing the area of an adjacent coking chamber, means for supplying heating gases to said heating passage,

a conduit comprising jointed elements communicating with said heating passage for withdrawing waste heat therefrom, jointed elements within said heating wall intermediate to said coking chamber and said conduit, said conduit being spaced from the inner surfaces of said heating wall except for certain of said intermediate jointed elements, the joints of said certain jointed elements being communicated with the said heating passage by substantial passageway means, whereby possible channels of joint communication between said coking chamber and the interior of said conduit are intermediately bypassed into the said heating passage.

3. In a coke oven having a coking chamber, a heating wall adjacent the coking chamber provided with a heating passageway, said heating wall being constituted by jointed refractory elements, a jointed refractory outlet conduit structure within said heating wall and communicating said heating passageway with the exterior of the coke oven, said conduit having a joint positioned within the boundary of said heating wall and being substantially spaced from the inner surfaces of said heating wall, and said heating wall having a substantial escape passageway communicating the joints of said heating wall in the vicinity of the joint of said outlet conduit to said heating passageway, thereby to by-pass into the heating passageway any gas escaping from the coking chamber through the joints in the heating wall and prevent its entry into said outlet conduit.

4. A coking oven, constructed of refractory elements jointed together, comprising a coking chamber, a hollow heating wall in position parallel to the coking chamber, the outer shell of the hollow heating wall being constructed of refractory bricks jointed together, means for supplying heating gases to said hollow wall, a waste heat withdrawal conduit and header-system built of refractory elements jointed together and located inside of said hollow heating wall preferably in its center plane, auxiliary jointed brickwork inside of said hollow heating wall, intermediate the waste heat withdrawal system and the outer shell of said heating wall, said auxiliary brickwork serving to form baffle walls and supporting means for said withdrawal system, those joints between the interior of the coking chamber and the interior of the withdrawal system, which are in contact with each other either directly or by virtue of the intermediate auxiliary brickwork and which are therefore adapted to draw distillate gases from the coking chamber into the withdrawal flues being locally widened into substantial passageways communicating with said flues.

5. A coking oven constructed of refractory elements jointed together, comprising a coking chamber, a hollow heating wall parallel to said chamber, the outer shell of said heating wall being constructed of refractory bricks jointed together, a system of heating flues inside of said wall jointed together, means for supplying heating gases to said flues, a conduit and header system inside of said wall jointed together for withdrawing waste heat from said flues, auxiliary jointed brickwork inside of said wall intermediate the outer shell and the waste heat withdrawal system for the formation of baffle walls and supporting means for said withdrawal system, and substantial passageway means provided in the joints located between said coking chamber and said withdrawal conduit and header system, said passageway means being in communication with

said heating flues and adapted to vent the pressure condition that may extend into the joints from either the withdrawal conduit and header system or from the coking chamber.

6. A coking oven constructed of refractory brickwork jointed together, comprising a coking chamber between hollow coking walls jointed together, baffle walls in said coking walls jointed together and forming heating flues between them, means for supplying heating gases to said flues, waste heat withdrawal conduit and header means jointed together and substantially internal of said coking walls, auxiliary intermediate brickwork jointed together for securing the location of said conduit and header means inside and outside of said coking walls, substantial passageway means being interposed in the joints of any of said jointed brickwork between the coking chamber and the conduit and header means, said passageway means communicating with said flues, and adapted to prevent direct flow of distillate gas from the coking chamber into the conduit and header means by venting it into said flues.

7. A coking oven constructed of refractory elements jointed together, comprising a coking chamber, a refractory coking wall, jointed together by coking wall joints, a plurality of refractory baffle walls in said coking wall for forming

heating flues inside of said wall, each of said baffle walls being jointed together by baffle wall joints, means for supplying heating gases to said heating flues, a waste heat withdrawal conduit and header system for removing waste heat from said heating flues to the exterior of said coking wall, said conduit and header system being jointed together by conduit joints, a portion of said joints being widened to form substantial passageway-means in all such locations where coking wall joints are in contact with conduit joints either directly or indirectly by way of baffle wall joints, said substantial passageway-means communicating with said heating flues.

10 5 15 20 25 8. A coking oven comprising a coking chamber, constructed of refractory elements jointed together, a system of heating flues therefor, means for supplying heating gases to said flues, a conduit system constructed of refractory elements jointed together for withdrawing waste heat from said flues, said conduit system being substantially internal of said heating flues, and substantial passageway means, communicating with said heating flues interposed between joints in the coking chamber and joints of the conduit system at all places where the chamber wall joints are in the vicinity of conduit joints.

FRANZ PUENING.
